UNITED STATES PATENT OFFICE.

GEORGE J. WINTER, OF BUFFALO, NEW YORK.

CUSHION SHOE.

Application filed January 15, 1924. Serial No. 686,397.

To all whom it may concern:

Be it known that I, GEORGE J. WINTER, a citizen of the United States, residing at Buffalo, in the county of Erie and State of New York, have invented new and useful Improvements in Cushion Shoes, of which the following is a specification.

My present invention pertains to cushion inner soles for boots, shoes and the like and it contemplates the provision of a simple and inexpensive cushioning means that forms a permanent and component part of the shoe.

The invention further contemplates the provision of cushioning means that are adapted to be secured on the inner sole of a shoe and this in such a manner as to produce a neat and finished appearance to the interior of the shoe.

Further objects and advantages of the invention will be fully understood from the following description and claims when the same are read in connection with the drawings accompanying and forming part of the specification, in which

Figure 1 is an inverted plan view of an inner sole equipped with my novel improvements.

Figure 2 is a top plan view of my inner sole cushioning means as showing a portion thereof in section.

Figure 3 is a longitudinal sectional view of the inner sole and cushioning means.

Figure 4 is a cross-section of the inner sole and cushioning means.

Similar numerals of reference designate corresponding parts in all the views of the drawings.

My novel improvements are secured on the ordinary well known leather or gem welt inner sole 1 that is channeled as indicated by 2 and stitched at 3.

A layer of lamb's wool felt 5 is cut to the exact size of the leather inner sole and

covers same snugly with the exception of the heel seat. This leaves a hollow space at the heel seat thus showing the leather of the inner sole at the heel portion thereof and is done for the purpose of heelng the shoe

as the nails would penetrate and clinch on the inner sole side of the cushioning means were the layer 5 initially extended to cover the heel seat. The cavity left at the heel is filled with the felt 12 that in turn is covered by the heel plate 13 after the shoe has been heeled and hence the nails are fully

covered and produce a perfect heel cushion. Provided in the felt 5 are a series of openings 14 for the purpose of allowing the foot to rest comfortably at the joints and at the same time the felt between this series of openings will support the arches between the joints of the foot thereby allowing perfect freedom of movement of the joints, separating the toes and preventing them from rubbing together and thus causing corns on the toe top or tips of the toes.

Adapted to completely cover the felt 5 and cut to exactly the same shape as the felt is a covering of canvas 6 that is stitched by the vertical stitching 7 to the felt and loose to the edge thereof. This strengthens the cushions and prevents them from wrinkling or bunching. I would distinctly have it understood that up to this point, the felt

and canvas are not secured to the inner sole but are free with respect thereto. When these members 5 and 6 have been stitched to each other they are secured to the inner smooth surface of the inner sole 1 by means

of cement and I then use a water-proof material preferably linen treated with rubber

8 that is slightly longer than the felt and is provided with a margin 9 of about $\frac{3}{8}$ of an inch which rests over the smooth side

85 of the inner sole and is stitched to the smooth top portion 10 by means of the stitching 11. The overlapping portion 9

to which the smooth inner surface 10 has

been stitched is then placed on the canvas

6 and is snugly cemented around the edges

and against the high portions of the channel 2 as illustrated. The cushion made up

in the manner illustrated is now ready to

be placed on the last. The upper is pulled

over for lasting and sewing to the lip of

the innersole with the overlap over-cushion

to the inner sole which is the usual manner

of making welt shoes. The shoes are then

heeled. The placing of the heel cushion

100 12 and plate 13 is now resorted to.

It will be manifest from the foregoing that a shoe equipped with cushioning means such as that specified will require no breaking-in and that it will not be necessary

105 for the wearer to suffer because of the fact that a shoe equipped with my novel inner sole will immediately conform to the foot upon putting on of the shoes. The inner sole makes the shoe absolutely water-proof

110 because of the overlapping water-proof material 9 and the openings 14 in the felt 5

act as ventilators in case of excessive perspiration and cause the perspiration to evaporate. It is a non-conductor of heat and hence may be worn with comfort in warm or cold weather as the felt cushion will cause the feet to retain their natural blood temperature.

Having described my invention, what I claim and desire to secure by Letters-Patent is:—

1. In a cushion shoe, the combination of an innersole having a smooth inner surface and a channelled outer surface, a felt pad having apertures therein and extending from the toe of the innersole to the base of the shank thereof, a canvas layer stitched to the felt and of the same shape as the felt; said felt and canvas being adapted to be secured to the smooth inner surface of the innersole, an overlapping water-proof material adapted to rest above the canvas, a smooth soft leather portion of the same configuration as the felt and stitched to the water-proof; said water-proof material being adapted to be cemented to the raised portion of the lip of the innersole on the outer surface and a portion of felt adapted to rest on the heel seat of the innersole and

a plate of leather adapted to be secured over the heel felt and having an overlapping portion that rests upon the shank portion of the smooth soft leather portion.

2. In a cushion shoe, the combination of an inner sole having a smooth inner surface and a lip arranged on its outer surface, a pad having openings therein and arranged to snugly fit the smooth surface and terminating at the lower end of the innersole shank, an independent heel plate formed of cushion material adapted to rest on the heel seat of the inner sole, a canvas cover of a configuration similar to that of the pad and adapted to be stitched thereto, a waterproof cover adapted to bear on the canvas and overlap the same and cemented to the side outer walls of the lip, a soft outer casing stitched to the canvas and adapted to completely cover same, and a heel cover having one end that bears on and is secured to the shank portion of the outer cover and adapted to bear on the heel plate, substantially as and for the purpose specified.

In testimony whereof I have hereunto set my hand.

GEORGE J. WINTER.
